(57) **CLAIM**

The ornamental design for a plate loader, as shown and described.

DESCRIPTION

FIG. 1 is a top perspective view of the plate loader according to our new design with a front panel open for access to a plate loading compartment of the plate loader.

FIG. 2 is a front view of the plate loader of FIG. 2.

FIG. 3 is a rear view of the plate loader of FIG. 2.

FIG. 4 is a side view of the plate loader of FIG. 2.

FIG. 5 is another side view of the plate loader of FIG. 2.

FIG. 6 is a top view of the plate loader of FIG. 2; and,

FIG. 7 is a bottom view of the plate loader of FIG. 2.

The broken lines in the figures illustrate unclaimed environment only and form no part of the claimed design.

1 Claim, 7 Drawing Sheets
